Fig. 1.

UNITED STATES PATENT OFFICE.

MILTON TIBBETTS, OF DETROIT, MICHIGAN, ASSIGNOR TO PACKARD MOTOR CAR COMPANY, OF DETROIT, MICHIGAN, A CORPORATION OF MICHIGAN.

MOTOR-CONTROL MECHANISM.

1,116,955.

Specification of Letters Patent. Patented Nov. 10, 1914.

Application filed December 31, 1910. Serial No. 600,293.

To all whom it may concern:

Be it known that I, MILTON TIBBETTS, a citizen of the United States, and resident of Detroit, Wayne county, State of Michigan, have invented certain new and useful Improvements in Motor-Control Mechanism, of which the following is a specification.

This invention relates to motor control mechanism and particularly to the control of the throttle valve, the intake valves and the spark advance mechanism. The invention is illustrated as applied to a hydrocarbon motor of the type in which air is compressed in the crank case or elsewhere and delivered to the cylinder at or near the end of the intake stroke for the purpose of augmenting the charge drawn in through the intake valve, and the valve control mechanism is particularly applied to the valve in the channel through which this augmenting charge of air passes from the crank case to the cylinder.

In a hydrocarbon motor having means for augmenting the charge as above described, it is desirable that the manual control lever shall act first upon the throttle valve and the augmenting valve to bring them into operation, and that thereafter the time of opening the augmenting valve shall be advanced relative to the closing of the regular inlet valve as the motor reaches higher speed. On the other hand, it is not desirable that the timing of the augmenting valve should be advanced at low speeds even though the throttle may be wide open and the augmenting valve doing full duty. It will be seen, therefore, that the timing of the augmenting valve should be advanced with the increase in speed of the motor rather than with the increase in power, otherwise the incoming charge of air would blow part of the explosive charge out through the regular intake valve and back into the carburetor, which it has not time to do at high speeds.

It is well known that in most hydrocarbon motors, particularly those used on motor vehicles, there is provided a spark advance mechanism by which the spark in the cylinder may be advanced as the speed of the motor increases. This spark advance mechanism may be controlled either by the operator or automatically as by a governor.

It is further desirable to have the entire control of the throttle valve and augmenting

valve under one control lever and the operation of this lever, therefore, would first be to open the throttle valve wide and move the cam shaft to operate the augmenting valve to its greatest degree, and then to advance the time of opening of the augmenting valve, the latter step being taken only after the motor has reached comparatively high speed. With this mechanism alone there would be no way by which the driver or operator could certainly know when he had reached the limit of opening of the augmenting valve and his only means of knowing that the movement of the control lever had passed beyond that stage and to a point where it advanced the time of opening of the augmenting valve would be by the sudden decrease in the power of the motor due to part of the explosive charge being blown back through the intake valve. To the uninitiated this condition of affairs would be confusing, and in any event it would be difficult to check the progress of the control lever at the exact point where the lever began to advance the time of opening of the augmenting valve, and particularly is this true when the controlling lever is operated by the driver's foot. The present invention overcomes this difficulty by providing a checking device or stop for the purpose of resisting the operation of the control lever at a point just before it begins to effect an advancement of the time of opening of the augmenting valve. This checking device may be in the form of a rigid stop whereby the advancement referred to can only be effected after the stop is withdrawn, or it may be a yielding stop whereby the control lever will be yieldingly resisted at the point referred to and by further pressure thereon it may be operated to advance the timing of the augmenting valve.

The checking device may be connected with the spark control mechanism or it may be connected with the governor, and in either event it will be rendered inoperative when the motor is running at high speed, in the first instance because the spark is practically always in advanced position when the motor is running at speed and the driver will, therefore, automatically withdraw the stop as he advances the spark, and in the second instance the stop will be automatically withdrawn at high speed by the action of the governor.

The objects of the invention are apparent from the above and will be brought out more particularly in the following detail description.

5 Referring to the drawings: Figure 1 is a side elevation and part section showing a hydrocarbon motor in which this invention is embodied; Fig. 2 is a vertical cross section through one of the motor cylinders; 10 Fig. 3 shows another form of the means for operating the checking device; Fig. 4 shows another form of the checking device; and Fig. 5 shows a combination of the two previous checking devices.

15 In the drawings are shown two cylinders 10 of a hydro-carbon motor, each cylinder of which is provided with inlet and exhaust valves on one side thereof, one of these valves being shown in Fig. 2 and indicated by the numeral 11, and with an augmenting valve 12, preferably arranged on the other side of the cylinder. The inlet and exhaust valves are operated in a well known manner by the cams on the cam shaft 13 driven by 20 the 2 to 1 gears 14 and 15 from the crank shaft. The augmenting valve 12 is also operated by a cam shaft indicated at 16 which is driven by similar gears 14 and 15.

An air inlet port 17 is arranged in one 25 side of the cylinder so that it is uncovered by the piston 18 only when the latter is at the top of its stroke to permit a charge of air to be drawn into the crank case 19, and this port is governed by a valve 20. The 30 crank shaft is shown at 21 and the connecting rod 22 connects it with the piston 18.

The augmenting valve 12 controls the 35 passage of air from the crank case to the cylinder, this air passing through the channel 23 and the port 24, which latter is arranged in the cylinder to be uncovered by the piston at the bottom of its stroke.

The cams 25 and 26 on the cam shaft 16 are so arranged and proportioned relative 40 to the position of the crank shaft that the valve 12 is opened at the end of the firing stroke for the purpose of admitting a charge of air from the crank case into the cylinder to scavenge the latter and again at the 45 end of the intake stroke for the purpose of augmenting the charge of combustible mixture previously drawn into the cylinder through the regular intake valve. The latter opening of the augmenting valve is governed entirely by the position of the cam 50 which operates it, this cam 26 being tapered, as shown particularly in Fig. 1, so that when the cam shaft 16 is in the position shown in full lines in Fig. 1 the cam 26 is 55 ineffective and the valve 12 is not opened, whereby no augmentation of the charge occurs. The cam shaft 16, however, is arranged to slide longitudinally by reason of its pin-and-slot connection 27, 28, with the 60 gear 14 shown in Fig. 1 whereby the higher 65 gear 14

portion of the cam 26 is brought into action and the valve 12 is lifted more or less at the end of the intake stroke for the purpose of augmenting the charge in the cylinder.

It will be seen that the slot 28 is straight 70 throughout the greater part of its length, but that the extreme forward end 29 thereof is arranged at a slight angle whereby when the pin 27 is moved into this end 29 the angular relation of the shaft 16 and the 75 gear 14 is slightly altered causing an advancement of the time of opening the augmenting valve relative to the position of the crank shaft or piston and consequently relative to the time of closing of the regular 80 inlet valve 11 through which the combustible mixture is drawn.

The cam shaft 16 is shifted longitudinally by the shifter rod 30 which is connected to it through a suitable yoke and groove connection, the yoke being shown in Fig. 2 at 85 30^a as entering an annular groove in the cam shaft 16, and this rod is connected to the accelerator pedal 31 by the link 32 and to the hand control rod 33 by the bell crank 90 lever 34 and springs 35 surrounding the link 32 and abutting against the stops 36 thereon. It will be understood that the hand control rod 33 may be locked in any desired position by any of the well known devices for 95 this purpose, and the accelerator pedal 31 may be depressed to operate the shifter 30 without disturbing the position of the hand control rod 33.

In Fig. 1 the intake pipe is shown at 37 100 in which is the butterfly throttle valve 38 operated by the arm 39 through the link 40 and rod 41, which latter is connected to the rod 32 through the spring 42 which is arranged between the stop 43 on the rod 41 105 and the stop 44 on the rod 32. A stop 45 is provided to limit the opening movement of the throttle valve.

From the above description it will be seen that upon depression of the accelerator 110 pedal 31 the cam shaft 16 is shifted simultaneously with the opening of the throttle valve 38 until the latter reaches its full opening and thereafter the cam shaft 16 is shifted independently, leaving the throttle in 115 wide open position. It will be understood that the low portion of the augmenting cam may be longer than shown to permit the throttle to be opened wide before the augmenting valve is brought into operation, if desired. 120 When the cam shaft 16 reaches the position shown in dotted lines in Fig. 1, the augmenting valve 12 is opening to the greatest degree, and from said position onwardly the pin 27 moves in the angular part 29 of the 125 slot 28 causing the timing of the augmenting valve 12 to be advanced relative to the position of the crank shaft, as above suggested. It will be observed that with only 130 the mechanism above described, the oper-

ator is in no position to know when the shaft 16 has reached the position in which it is shown in dotted lines in Fig. 1, and if he moves the cam shaft 16 to its extreme forward position when the motor is running at low speed, the opening of the augmenting valve would be sufficiently advanced to blow part of the combustible charge out of the cylinder through the carburetor before the regular intake valve was closed. This could not take place, however, when the motor was running at high speed as there would not be sufficient time for the augmenting air to blow through the cylinder, and it will be seen, therefore, that the advancement of the opening of the augmenting valve is useful only at high motor speeds.

To prevent the advancement of the timing of the augmenting valve except at high speeds, a checking device shown in Fig. 1 in the form of a wedge 46 is provided between an abutment 47 formed as a part of the motor base or crank case, and a block 48 on the shifter rod 30 whereby the forward movement of the rod 30 is resisted or arrested when the cam shaft 16 reaches the position shown in dotted lines in Fig. 1.

In Fig. 1 the wedge 46 is connected through bell crank 49, arm 50 and rod 51 with the spark advance mechanism, it being understood that the spark advance mechanism may be either manually or governor controlled as in either case the spark is advanced with the speed of the motor.

As shown in Fig. 1 the spark advance mechanism consists of a control lever 52, bell crank lever 53, rod 54 and linkage 55 connected to the rocking part 56 of the magnet 57. The connection of the arm 50 with the spark advance mechanism is such that there is no movement of the arm 50 until the control lever 52 is partly advanced as shown in Fig. 1, but thereafter the bell crank 53 strikes the arm 50 and carries the latter with it whereby the wedge 46 is withdrawn and the shifter rod 30 is permitted to continue its forward movement and advance the position of the crank shaft 16. A spring 49^a retains the wedge normally in operative position.

In Fig. 3 the wedge 46 is directly coupled to a governor 58 of the hydraulic type, which is shown as operating to its maximum extent whereby the wedge 46 has been withdrawn and the shifter rod 30 may be moved to its fullest extent forwardly for advancing the position of the cam shaft 16.

Fig. 4 shows another form of checking device comprising a yielding stop 46^a and spring 46^b. It will be seen that with this form, the movement of the shifter rod 30 is resisted at the proper point, but by using additional force on the accelerator pedal the resistance may be overcome and the cam

shaft 16 advanced to its limit. This checking device acts to notify the operator that he has reached the point where the cam shaft 16 is about to begin its advance movement.

A combination of the two previously described forms of checking devices is shown in Fig. 5 wherein the wedge 46 is controlled by the spark advance mechanism as in the other case and the yielding stop 46^a acts the same as that shown in Fig. 4 until the spark is fully advanced when said stop 46^a is rendered inoperative.

Having thus described my invention, what I claim is:

1. In a hydrocarbon motor, the combination with the cylinder and a valve mechanism for admitting the charge to the cylinder and for subsequently augmenting said charge, said mechanism having a variable action as regards the augmenting feature thereof, of a checking device adapted to resist the variable action of said mechanism.

2. In a hydrocarbon motor, the combination with the cylinder and ports therein, means for controlling said ports to admit a combustible charge and to augment said charge, the timing of said means being variable relative to the motor crank shaft, and means for varying said timing, of a checking device adapted to resist the operation of said varying means.

3. The combination with a hydrocarbon motor having intake and exhaust valves and a valve for admitting an augmenting charge of air to the cylinder after the admission of the explosive charge through the intake valve, of means for operating said valves including means for advancing the opening of the augmenting valve relative to the time of closing of the intake valve, means for shifting the advancing mechanism, and a checking device adapted to resist the operation of the shifting means.

4. The combination with a hydrocarbon motor having intake and exhaust valves and a valve for admitting an augmenting charge of air to the cylinder after the admission of the explosive charge through the intake valve, of means for operating said valves including means for advancing the opening of the augmenting valve relative to the time of closing of the intake valve, means for shifting the advancing mechanism, a checking device adapted to resist the operation of the shifting means, and manually controlled means for rendering the checking device inoperative.

5. The combination with a hydrocarbon motor having intake and exhaust valves and a valve for admitting an augmenting charge of air to the cylinder after the admission of the explosive charge through the intake valve, of means for operating said valves including means for advancing the opening of the augmenting valve relative to the time of

- 4
1. The combination with a hydrocarbon motor having valves and valve operating mechanism including an augmenting valve and a tapered cam for operating it, of means for shifting said tapered cam to increase the opening of said valve and then advance the time of opening thereof, a checking device to resist the shifting movement of said cam for the advance timing effect without affecting the increased opening effect, and means for rendering the checking device inoperative.
2. The combination with a hydrocarbon motor having intake and exhaust valves and a valve for admitting an augmenting charge of air to the cylinder after the admission of the explosive charge through the intake valve, of means for operating said valves including means for advancing the opening of the augmenting valve relative to the time of closing of the intake valve, means for shifting the advancing mechanism, a checking device adapted to resist the operation of the shifting means, spark advance mechanism, and means controlled by the position of the spark advance mechanism for rendering the checking device inoperative.
3. In a hydrocarbon motor, the combination with the cylinder and the intake and exhaust mechanism, of a valve mechanism having a part arranged normally in inoperative position, a control lever connected to bring said part into operative position, a checking device adapted to resist the movement of said control lever, and means for rendering said checking device ineffective.
4. In a hydrocarbon motor, the combination with the cylinder, the intake and exhaust mechanism and the throttle valve, of a valve mechanism having a part arranged normally in inoperative position, a control lever adapted to open said throttle valve, and connections from said control lever to said valve mechanism for moving said part to operative position after the throttle valve is opened a predetermined amount.
5. The combination with a hydrocarbon motor having a valve, a valve shaft geared to the crank shaft and having means connected therewith to operate said valve, said valve shaft being shiftable to a predetermined point to increase the length of time for the opening of said valve, means in the connection between said valve shaft and the crank shaft whereby shifting said valve shaft beyond said point causes an advanced opening of said valve relative to the crank shaft position, a manually controlled lever for shifting said valve shaft, and a checking device adapted to come into operation to check the shifting movement of said valve shaft at said predetermined point.
6. The combination with a hydrocarbon motor having valves and valve operating mechanism including an augmenting valve and a tapered cam for operating it, of means for shifting said tapered cam to increase the opening of said valve and then advance the time of opening thereof, and a checking device to resist the shifting movement of said cam for the advance timing effect without affecting the increased opening effect.
7. The combination with a hydrocarbon motor having valves and valve operating mechanism including an augmenting valve and a tapered cam for operating it, of means for shifting said tapered cam to increase the opening of said valve and then advance the time of opening thereof, a checking device to resist the shifting movement of said cam for the advance timing effect without affecting the increased opening effect, and means for rendering the checking device inoperative.
8. The combination with a hydrocarbon motor having means for augmenting the charge, means for regulating the degree of augmentation, and means for varying the timing of said augmenting means, of a device connected to shift said regulating and varying means, the parts being so constructed and arranged that the movement of the shifting device first operates the regulating means to give the greatest degree of augmentation and thereafter operates the varying means to advance the timing of the augmenting means, and a checking device arranged to resist the movement of the shifting device as it is about to operate upon the varying means.
9. The combination with a hydrocarbon motor having means for augmenting the charge and means for varying the degree of augmentation and the timing thereof, of a rod connected to shift said varying means to first increase the degree of augmentation and then to advance the timing thereof, an abutment, a block on said rod adapted to move toward and from said abutment with the shifting movements of said rod, a wedge between said block and said abutment and forming a check or stop to arrest the movement of said rod before it begins to effect an advance in the timing of the augmenting means, a spark advance mechanism, and connections from the latter to said wedge whereby the wedge is withdrawn when the spark is advanced to permit said rod to effect an advancement of the augmenting means.
10. The combination with a hydrocarbon motor having valves and valve operating mechanism including an augmenting valve and a tapered cam for operating it, of means for shifting said tapered cam to increase the opening of said valve and then advance the time of opening thereof, and a checking device to resist the shifting movement of said cam for the advance timing effect without affecting the increased opening effect.
11. The combination with a hydrocarbon motor having valves and valve operating mechanism including an augmenting valve and a tapered cam for operating it, of means for shifting said tapered cam to increase the opening of said valve and then advance the time of opening thereof, a checking device to resist the shifting movement of said cam for the advance timing effect without affecting the increased opening effect, and means for rendering the checking device inoperative.
12. The combination with a hydrocarbon motor having means for augmenting the charge, means for regulating the degree of augmentation, and means for varying the timing of said augmenting means, of a device connected to shift said regulating and varying means, the parts being so constructed and arranged that the movement of the shifting device first operates the regulating means to give the greatest degree of augmentation and thereafter operates the varying means to advance the timing of the augmenting means, and a checking device arranged to resist the movement of the shifting device as it is about to operate upon the varying means.
13. The combination with a hydrocarbon motor having means for augmenting the charge, means for varying the timing of said augmenting means, and a spark advance mechanism, of means for shifting said spark advance mechanism and said varying means whereby the timing of said augmenting means depends upon the position of the spark advance mechanism.
14. The combination with a hydrocarbon motor having means for augmenting the charge and means for varying the degree of augmentation and the timing thereof, of a rod connected to shift said varying means to first increase the degree of augmentation and then to advance the timing thereof, an abutment, a block on said rod adapted to move toward and from said abutment with the shifting movements of said rod, a wedge between said block and said abutment and forming a check or stop to arrest the movement of said rod before it begins to effect an advance in the timing of the augmenting means, a spark advance mechanism, and connections from the latter to said wedge whereby the wedge is withdrawn when the spark is advanced to permit said rod to effect an advancement of the augmenting means.
15. The combination with a hydrocarbon motor having means for augmenting the charge and means for varying the degree of augmentation and the timing thereof, a rod connected to shift said varying means to first increase the degree of augmentation and then to advance the timing thereof, an abutment, a block on said rod adapted to

move toward and from said abutment with the shifting movements of said rod, and a yielding stop between said block and said abutment for resisting the movement of said rod before it begins to effect an advance in the timing of the augmenting means.

16. The combination with a hydrocarbon motor having means for augmenting the charge and means for varying the degree of augmentation and the timing thereof, a rod connected to shift said varying means to first increase the degree of augmentation and then to advance the timing thereof, an abutment, a block on said rod adapted to move toward and from said abutment with the shifting movements of said rod, a yielding stop between said block and said abutment for resisting the movement of said rod before it begins to effect an advance in the timing of the augmenting means, a wedge between said yielding device and said abutment, a spark advance mechanism, and connections from the latter to said wedge whereby the wedge is withdrawn when the spark is advanced to permit said rod to effect an advancement of the augmenting means without interference from said yielding stop.

17. In a hydrocarbon motor the combina-

tion with the cylinder, means for admitting the main charge thereto, means for subsequently augmenting the admitted charge, and means adjustable for varying the timing of said augmenting means, of a checking device adapted to resist the operation of said varying means.

18. In a hydrocarbon motor the combination with the cylinder, means for admitting the main charge thereto, means for subsequently augmenting the admitted charge, and means for varying the timing of said augmenting means, of a device for shifting said timing means, and a checking device adapted to resist the operation of said shifting device.

19. In a hydrocarbon motor, the combination with the cylinder, variable means for introducing into the cylinder a volume of air under pressure in addition to the regular charge due to piston displacement, of a checking device adapted to resist the varying action of said means.

In testimony whereof I affix my signature in the presence of two witnesses.
